Q.S. 2294

Sarah E. Cook, of Philadelphia, Penn.
Letters Patent No. 2294 - Dated April 24, 1866.
Antidated March 20, 1866.
Design for an Ornament for the Head.

The schedule referred to in these Letters Patent and making part of the same.

To all whom it may concern:

I, Sarah E. Cook, of Philadelphia, in the
State of Pennsylvania, of Pennsylvania, have invented or produced
a new and original design for an ornament for the head, and do hereby
declare the accompanying drawing with the following description of the
same to form a full, clear and exact description of the said design.

The figure is the accompanying drawing, representing a
row of natural or artificial hair, fitted to form an ornament
for the head.

I claim, the design for an ornament for the head, substantially
as shown in and for the accompanying drawing,
In testimony whereof, I have signed my name to this specification in
the presence of two subscribing witnesses,
Witnesses:

Charles E. Foster,
John White
